John J. Bockee Jr.

United States Patent Office.

JOHN J. BOCKÉÉ, JR., OF NEW YORK, N. Y.

Design No. 4,837, dated April 25, 1871.

DESIGN FOR A LARD-PAIL.

The Schedule referred to in these Letters Patent and making part of the same.

To all whom it may concern:

Be it known that I, JOHN J. BOCKÉÉ, Jr., of the city, county, and State of New York, have invented and produced a Design for a Metal Can, of which the following is a specification.

In the accompanying drawing—

Figure 1 is a plan, and

Figure 2 is a side view of a can made according to my design.

The body of the can is of taper form vertically, being larger at the bottom than at the top, and in its transverse or horizontal section is elliptical shaped.

Said can has formed on it moldings *a b*, the form of which is clearly represented in fig. 2 of the drawing.

I do not claim broadly a taper-molded can; but

I claim—

The design for a metal can as described, and as represented in the drawing.

JOHN J. BOCKÉÉ, JR.
